(57) **CLAIM**

The ornamental design for a chair, as shown and described.

DESCRIPTION

FIG. 1 is a perspective view of a chair showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another rear side perspective view thereof; and, FIG. 9 is an enlarged view of a portion labeled '9' in FIG. 7.

The broken lines in the drawings depict portions of the chair that form no part of the claimed design. Additional broken lines in FIGS. 7 and 9 show enlarged areas and form no part of the claimed design.

1 Claim, 9 Drawing Sheets
